UNITED STATES PATENT OFFICE.

THOMAS DOWN, OF TORONTO, CANADA, ASSIGNOR OF ONE-HALF TO JAMES JEFFREY, OF SAME PLACE.

CHEMICAL-ENGINE.

SPECIFICATION forming part of Letters Patent No. 611,030, dated September 20, 1898.

Application filed July 30, 1897. Serial No. 646,542. (No model.)

To all whom it may concern:

Be it known that I, THOMAS DOWN, manufacturer, of the city of Toronto, in the county of York and Province of Ontario, Canada, 5 have invented certain new and useful Improvements in Chemical-Engines, of which the following is a specification.

The object of my invention is to devise a simple, light, and easily-operated chemical- 10 engine; and it consists, essentially, in the improved construction of the cylinder, in which the acid-bottle is made rotatable instead of the cylinder for the purpose of mingling the acid and the alkaline solution, and in such 15 details of construction as are hereinafter more specifically described and then definitely claimed.

Figure 1 is a sectional side elevation of my improved engine. Fig. 2 is an enlarged section 20 of the acid-bottle end of the cylinder. Fig. 3 is a sectional elevation of the acid-bottle and cage at right angles to Fig. 2. Fig. 4 is an end elevation showing the bearing-plate on the end of the cylinder. Fig. 5 is a sectional plan view of the central band of the acid-bottle cage. Fig. 6 is a sectional plan 25 view of the under side of the upper ring of the acid-bottle cage.

In the drawings like letters of reference 30 indicate corresponding parts in the different figures.

A is the frame of the engine, of suitable construction, to which frame the pillow-stays B, carrying the cylinder or cylinders, are connected. The step C is also suitably supported on the frame of the machine.

D is a cylinder, of which two are preferably used, though only one is seen in the drawings.

E is the hose-reel, supported on the top of 40 the engine and provided in the usual manner with a hollow trunnion F, connected by the pipe G with the cylinder, which pipe is preferably provided with a three-way cock H when two cylinders are used.

45 On reference to Figs. 1, 2, and 4 the method of supporting the cylinder will be readily understood. A bearing-plate I is suitably secured to each end of the cylinder. Each bearing-plate has a downwardly-depending flange

a extended out therefrom to fit over the pillow-stay B, to which it is securely bolted. At the acid-bottle end of the cylinder the bearing-plate has a sleeve b extending through it to receive the end of the shaft J, a suitable stuffing-box c being screwed on the outer end 55 of the sleeve to form a water and air tight joint between the two. Connected to the end of the shaft J is a handle K, preferably made of the hollow form shown in Fig. 2.

L is an extension of the handle, pivoted at 60 d to the part K.

M is a flat spring adapted to bear against the flat side of the extension L near its pivot, so as to tend to retain it in the position indicated and yet permit the extension to be 65 drawn out at right angles when it is desired to revolve the shaft J.

N is a small latch centrally pivoted at the upper end of the handle K. The outer end of this latch is pivotally connected with the 70 extension L below its pivot by means of the pitman O. Thus the drawing down of the extension L will depress the inner end of the latch N. This end normally fits between the lugs e, formed on the bearing-plate I. (See 75 Figs. 2 and 4.)

The shaft J is supported within the cylinder on the bearings P and has arms Q depending therefrom, to the ends of which a chain R is attached, which normally lies upon the 80 bottom of the cylinder. The jarring of this chain while the engine is in motion tends to stir up the soda in the solution. When the shaft J is rotated, the soda is still further stirred up, so as to make it combine freely 85 with the acid poured into it. Below the plug S the shaft is divided to form two half-rings f and g, the two parts being bolted or riveted together at h. A series of upright bars i are cast with each half-ring and two half-rings j 90 and k are cast therewith and suitably riveted or bolted together, the whole of the parts just described forming a cage T, within which the acid-bottle U may be supported. The acid-bottle is loosely surrounded by a skeleton 95 jacket V, formed of the bottom plate l, the central band m, and the flanged upper band n, connected together by two or more rods o.

As the flange of the band *n* extends over the shoulder of the bottle, the latter is securely held within its jacket.

p is a cap or plug suitably fitted to the neck 5 of the bottle.

A' is a bail suitably pivoted on two opposite rods *o* and so shaped and proportioned as to fit closely upon the top of the cap *p*, and thus retain it in position. A projection *q* is 10 formed on this band, which is adapted to come into contact with one of the projections *r* upon the plug *S* when the acid-bottle is tipped, as hereinafter described.

s and *t* are lugs formed upon the bands *m* 15 and *n*, which are shaped to fit the recesses *u* and *v*, formed in the rings of the cage *T*. The recesses *v* are formed with a shoulder, as shown, to prevent the lugs *t* passing through them, thus affording a support for the jacket 20 of the bottle, which is slipped into position, as shown in Fig. 3.

w are spring-catches connected, respectively, to the half-rings *f* and *g* and adapted to engage with the flanged band *n* of the 25 jacket *v*, thus securely retaining the bottle in position in the cage.

The operation of the engine is substantially as follows: The extension *L* of the handle *K* is turned outwardly and the latch *N* thus released. The handle is then turned till the 30 position of the acid-bottle is reversed. As the acid-bottle swings the bail *A'* comes in contact with one of the projections *r*, and the cap *p* is thus released, permitting the acid to flow 35 freely into the contents of the cylinder, generating a large quantity of carbonic-acid gas, and the engine is then ready for use. In case of there being any liability of the cap *p* sticking 40 to form projections *x* thereon, against which the bail *A'* will strike, giving the cap a sufficient jar to loosen it. After the acid-bottle has been emptied it may be removed through the plug *S* and a new one inserted in the cage *T*, a fresh charge of water and 45 alkali being placed in the cylinder at the same time.

What I claim as my invention is—

1. In a chemical-engine, a stationary cylinder provided with a discharge-outlet and a 50 recharging-opening closed by a suitable plug, in combination with a suitably-journalized rotatable shaft extending through one end of the cylinder; an acid-bottle inclosed in a skeleton jacket provided with one or more lugs; a cage supported by the said shaft and recessed to receive and support the said lugs; a spring-catch connected to the cage and adapted to engage the jacket of the acid-bottle to retain it in the cage; a cap for the bottle; a bail pivoted to the jacket and adapted to retain the cap in position; and a projection upon the cylinder with which the bail will engage when the shaft is rotated, substantially as and for the purpose specified.

65 2. In a chemical-engine, a stationary cylinder provided with a discharge-outlet and a

recharging-opening closed by a suitable plug, in combination with a suitably-journalized rotatable shaft extending through one end of the cylinder; an acid-bottle inclosed in a 70 skeleton jacket provided with one or more lugs; a cage supported by the said shaft and recessed to receive and support the said lugs; a spring-catch connected to the cage and adapted to engage the jacket of the acid-bottle to retain it in the cage; a cap for the bottle; provided with a teat to one side of the center; a bail pivoted to the jacket and adapted to retain the cap in position; and a projection upon the cylinder with which the bail will engage when the shaft is rotated, substantially as and for the purpose specified.

3. In a chemical-engine, a stationary cylinder provided with a discharge-outlet and a recharging-opening closed by a suitable plug, 85 in combination with a suitably-journalized rotatable shaft extending through one end of the cylinder; an acid-bottle suitably supported by the said shaft; a cap for the said bottle; a pivoted bail adapted to retain the cap in position; and a projection upon the cylinder with which the bail will engage when the shaft is rotated, substantially as and for the purpose specified.

4. In a chemical-engine, the combination 95 of the frame *A*, the cylinder *D*, the pillow-stays *B* depending from the frame, and the bearing-plates *I*, connected to the cylinder and provided with flanges *a*, said flanges being securely bolted to said stays, whereby the 100 stays, cylinder, bolts, &c., act to "stay" the frame, substantially as and for the purpose specified.

5. In a chemical-engine, the combination of the frame *A*; cylinder *D*, pillow-stays *B*; 105 bearing-plates *I*, provided with flanges *a* secured to the pillow-stays; sleeve *b*, extending through one bearing-plate; a suitably-journalized shaft *J*, extending through said sleeve; and the handle *K*, substantially as and for 110 the purpose specified.

6. In a chemical-engine, the combination of the frame *A*; cylinder *D*, pillow-stays *B*; bearing-plates *I*, provided with flanges *a*, a sleeve *d* extending through one bearing-plate, a suitably-journalized shaft *J* extending 115 through said sleeve, and handle *K*, the extension *L*, pivoted on the said handle; the latch *N*, centrally pivoted on said handle; the pitman *O*, pivotally connecting the latch *N*, and extension *L*, and the lugs *e*, upon the plate *I*, with which the said latch engages, substantially as and for the purpose specified.

7. In a chemical-engine, the combination of the frame *A*; cylinder *D*, pillow-stays *B*; 125 bearing-plates *I*, provided with flanges *a*, secured to the pillow-stays; a sleeve *d* extending through one bearing-plate, a suitably-journalized shaft *J* extending through said sleeve, and handle *K*, the extension *L*, pivoted 130 on the said handle; the latch *N*, centrally pivoted on said handle; the pitman *O*, pivot-

ally connecting the latch N, and extension L; the lugs e, upon the plate I, with which the said latch engages; and a spring M, adapted normally to retain the extension in its closed position, substantially as and for the purpose specified.

8. In a chemical-engine, the combination of the frame A, the cylinder D, suitably secured thereto, the sleeve b extending through one end of the cylinder, a suitably-journalized shaft extending through the said sleeve, the handle K, connected to the end of the said shaft, the extension L, pivoted on said handle, the latch N, centrally pivoted on the said handle, the pitman O, pivotally connected to the latch N, the extension L, lugs e suitably carried upon the end of the cylinder with which the said latch engages, and a spring M, adapted normally to retain the extension in its closed position, substantially as and for the purpose specified.
9. In a chemical-engine, the combination of the frame A, the cylinder D, suitably secured thereto, the sleeve b extending through one end of the cylinder, a suitably-journalized

shaft extending through the said sleeve, the handle K connected to the end of the said shaft, the extension L, pivoted on the said handle, the latch N, centrally pivoted on the said handle, the pitman O, pivotally connected to the latch N, the extension L, lugs e suitably carried upon the end of the cylinder with which the said latch engages, and a spring M, adapted normally to retain the extension in its closed position, substantially as and for the purpose specified.

10. In a chemical-engine, the combination of a frame, having pillow-stays depending therefrom, a cylinder having bearing-plates I connected thereto and provided with flanges a, the said pillow-stays being secured to said flanges between them and the cylinder, substantially as and for the purpose specified.

Toronto, July 27, 1897.

THOMAS DOWN.
